ABSTRACT: A sash-construction having a notch against which a swing window or similar closing element, particularly a window swinging outwardly, is capable of being stopped, said window with its hinges is fixed to a separate narrow panel which is slideable in the plane of the normally closed sash and with the panel ends being guided with respect to the mutually parallel sash-sills. The ends of the narrow panel carrying the window hinges are in cooperative relation with a profile fillet applied to sills or posts. The slideable narrow panel carrying the window hinges is formed near its ends with a slipper or similar slide element, capable of slidably cooperating with the profile fillet present on the sill or post in question, while the edge of the panel carrying the window hinges abuts a case-shaped end of a profile fillet fixed to a sash-portion in which case a resilient elastic draught-strip is secured.

SASH-CONSTRUCTION

This invention relates to a sash-construction having a notch against which a swing window or similar closing element, particularly a window swinging outwardly, is capable of being stopped.

In practice, especially in high-rise construction, difficulties are experienced when cleaning the windowpanes on the outside. When the dimensions of the window are not too great, one may manage with a hand tool such as a cleaning gear held in a clamp which is fixed to a pole. This, however, is uneasy and certainly not undangerous. With somewhat greater window dimensions it is not possible to clean the window on its outside from inside.

The invention has for its objective the provision of a sash-construction of the type described above wherein the disadvantages pictured hereinabove are removed. According to the invention this is achieved in that the window with its hinges is fixed to a separate narrow panel part which is slidable within the closed plane of the sash and with its ends guided with respect to the mutually sash-sills. The narrow panel is further preferably provided with one or more ventilation windows or grids which are selectively openable.

The construction of the invention makes it possible to move the attached narrow panel window in its opened position together with the part as a result of which and through the related formed opening, the outside surface of the window becomes accessible and can be cleaned from inside the building.

The invention may be applied to a window as well as to a door, both of which are rotatable on a horizontal shaft. In the latter case the window, in its center, is made to hingedly rest on brackets, which latter in turn are hingedly fixed to e.g. the sash-posts.

It is efficient when the ends of the panel carrying the window hinges are in cooperative sliding relation with a profile fillet as applied to the sills when the sash and panel move horizontally, or as applied to the posts of the sash when the sash and panel are mounted to move vertically.

For reducing friction, the slidable panel part carrying the window hinges is formed near its ends with a slider or similar slide element, capable of slidably cooperating with the profile fillet of the related sill or post part of the window. This measure ensures an easy sliding of the panel part carrying the hinges, thereby doing away with the necessity of chiseling out special grooves.

For achieving an efficient sealing, the longitudinal edge of the panel carrying the window hinges abuts a case-shaped end of a profile fillet fixed to an adjacent edge of the related sash-part, in which case a resilient elastic draught-strip is secured.

The invention is explained below with reference to the drawing, in which:

FIG. 1 shows front elevational view of the sash-construction of the invention with the window in its closed position.

FIG. 2 is a front view of the sash-construction of the invention with the window opened and moved into a position in which it can be readily cleaned from inside and

FIG. 3 enlarged, fragmentary cross-sectional view taken substantially on the line III-III of FIG. 2.

FIG. 4 a similar cross-sectional view taken on the line IV-IV of FIG. 2.

The sash, which has opposite top side, bottom side, and lateral side portions, and may consist of wood is represented by 1, while the window 2 is provided with a window pane 3. The window 2 is swingingly mounted in the sash by means of suitable hinges 4 and is designed preferably to be swung outwards. According to the invention the hinges 4 are fixed in a narrow panel or part 5 which is disposed slideably in a cross direction, i.e. within the closed plane of the window and is guided therein on the upper sill 6 and the lower sill 7. Panes 8, 9, 10 or 11 can be arranged in the part 5, or ventilation grates or the like which, if desired, may be of the type admitting of being selectively closed or opened.

By moving the panel 5 as shown in FIG. 2 when the window is opened, a second opening 12 is provided enabling the window 2 to be cleaned in its opened position from inside.

A normal dog-lock is represented by 13 in FIG. 2 with the aid of which the window 2 can be locked in its closed position.

The sash-sills 6 and 7 are formed with a suitable profile fillet or track 14 as represented in section in FIGS. 3 and 4.

A glider or glide shoe 15 secured to the panel 5 by means of a T-profile bracket 16, as with the aid of screws, is complementally formed with a track or guideway to be in cooperative sliding relation with said profile fillet 14. The glider 15 may be made from synthetic material whereas for the track or profile fillet 14 and/or the T-profile 16, respectively, preferably a noncorrosive material, such as aluminum is chosen.

On its outer face side of abutment with the window 2, the profile fillet 14 is formed with a grooved case 17 in which the thickened portion of a draughtproof means 18 in the shape of a resilient weather strip is secured. Furthermore the case 17 forms the stop for the window 2 in its closed position.

The lower sill 7 is also provided preferably with a similar profile fillet 14 which cooperates with a like glider 15 which is secured to the part 5 in the way described hereinbefore. Said profile fillet 14, as shown in FIG. 4, has also as its object to guide the spanner or the casing 19 of a window adjusting rod.

As shown in FIG. 1, in the closed position of the window 2, part 5 abuts the turned-off resilient strip 20 embedded in a profile fillet in a known manner. Thus an efficient draught exclusion is provided between the panel 5 when it abuts the sash-post 21.

It should be observed that the details as shown in FIG. 3 have been omitted from FIG. 4 because the view is taken on line IV-IV at a point beyond the lower glider, wherein the profile fillet is in cooperative relation with a like glider which is fixed to the slidable window panel part 5.

Though drawn and described with reference to a window, door or similar closing element which is rotatable on a vertical hinge-shaft, the invention may equally be applied, as already observed before, to any element capable of swinging around a horizontal hinge-shaft. The panel part comprising the hinge-shaft thusly is slidable in a vertical sense is mounted then for cooperation and slidable movement within and between the opposed upright sash-posts. Then the closing element rests in its center hingedly on brackets which in turn are hingedly fixed to said upright sash-posts 21.

It is apparent from the foregoing that a novelly improved frame and sash construction has been evolved which achieves the objectives and advantages set forth throughout the specification.

I claim:

1. A frame (1) and sash construction for mounting a pivotally swingable window, door and the like unit, wherein said frame has pairs of opposite side portions, including sills and posts, and said unit preferably swings outwardly about a pivot axis and having means capable of limiting the extent of outward movement, comprising in combination:

- a window unit (2) for mounting within the open frame (1) to selectively close and open the frame opening thereof;
- a separate narrow panel (5) disposed so as to have the longitudinal plane of its planar surface coextensive with the plane of said window unit when said window unit is in a closed condition, said panel (5) being mounted for slidable movement within its longitudinal plane, and hingedly attached at one longitudinal side to a corresponding side of said window or like unit (2), and the opposite longitudinal side adapted to operatively sealingly engage with one side of said frame (1) in a free unattached manner;
- a profile fillet or track (14) removably attached to one pair of opposite side portions of said frame (1) in non-coplanar relation to said unit and panel for cooperation therewith by said slidable panel; and
- means operatively connecting said panel (5) adjacent its opposite longitudinal ends for sliding engagement upon the respective tracks (14) of paragraph c;

e. thereby enabling said window unit (2) to be serviced on its normally unaccessible outer surface when said window unit is pivotally opened and said attached panel (5) accordingly slidably moves away from its engagement with a side of the frame (1) to provide an access opening therebetween.

2. A frame and sash construction as defined in claim 1, wherein said profile fillets or tracks (14) include elongated portions coextensive therewith which project in a common coplanar relationship to constitute stop abutments (17) for the said unit (2) when in its closed condition.

3. The construction as defined in claim 2, further including draught and weather sealing strips means (18) disposed within an elongated groove provided in said stop abutments (17), which sealing strips (18) also are engaged by the marginal edges of said window unit (2) and panel (5) when in the closed condition.

4. The construction as defined in claim 1 wherein the means of paragraph d include a glider or glide shoe (15) having a recess of complementally shaped cross section to that of said track's gliding surface, with means attaching said glide shoes (15) to said panel (5).

5. The construction as defined in claim 4 wherein the glide shoes are fabricated of a synthetic material having antifriction qualities.

6. The construction as defined in claim 1 wherein the unit (2) and panel (5) are hingedly joined by a plurality of spaced hinges having a common hinge or pivot axis, and said axis is vertically disposed relative to the frame (1), whereby the

tracks (14) of paragraph c are attached to horizontal sill portions of the frame (1) and the means of paragraph d are in cooperative relation with said sill-applied tracks.

7. The construction as defined in claim 1 wherein the unit (2) and panel (5) are hingedly joined by a plurality of spaced hinges having a common hinge for pivot axis, and said axis is horizontally disposed, whereby the tracks (14) of paragraph c are attached to opposed vertical post portions of the frame (1) and the means of paragraph d are in cooperative relation with said post applied tracks.

8. The construction as defined in claim 1, wherein the panel (5) is provided with at least one selectively openable ventilation pane or grid (8-11).

9. The construction as defined in claim 1 further including a profile fillet having frame case-shaped end with a resilient weather strip (20) seated therein, said fillet disposed along the side of said frame (1) so that said opposite longitudinal side of the panel (5) as defined in paragraph b sealingly engages with said weather strip (20) when the unit (2) is in a fully closed condition within the frame (1).

10. The construction as defined in claim 1, wherein the means capable of limiting the extent of outward movement of the unit include an adjusting rod pivotally connected to the unit (2) and to a casing (19), said casing (19) having a complementally formed groove or slideway which complementally seats on, guides along and is retained in position by and generally coplanar with that of one of said tracks (14).
